Daniel S. Breman
ATTORNEY

UNITED STATES PATENT OFFICE

PASQUALE NOTARIANNI, OF DETROIT, MICHIGAN

WRENCH

Application filed January 17, 1931. Serial No. 509,439.

The invention relates to improvements in wrenches and particularly to an improved demountable adjustable pipe wrench.

An object of the invention is to provide an improved pipe wrench with a readily adjustable interchangeable gripping jaw.

Another object is to provide an improved wrench with means to facilitate adjustment of the gripping jaw with one hand.

Another object is to provide a wrench of the character referred to which is inexpensive to manufacture, will withstand hard usage, and is arranged to grip positively an object.

The foregoing and such other objects of the invention as will appear hereinafter as the description proceeds, will be more readily understood from a perusal of the following specification, reference being had to the accompanying drawing, in which:

Fig. 1 is an elevational view, partly in section, of the improved wrench.

Fig. 2 is a fragmentary elevational view of the improved wrench, partially disassembled.

Fig. 3 is a transverse sectional view, taken 25 on line 3—3 of Fig. 1.

Fig. 4 is a fragmentary elevational view of a gripping jaw shank, showing serrations thereon.

Pipe wrenches, or "Stillson wrenches" as 30 they are commonly termed, of the usual construction, necessarily require the use of both hands to effect adjustment of the gripping jaw. The capacity of such wrenches also is limited, thus necessitating keeping on hand a 35 complete set of such wrenches consisting of various sizes.

The improved pipe wrench hereinbefore referred to, is of such a construction as to require but one hand to effect instant adjustment of the gripping jaws. The improved construction also provides for substitution of one of the gripping jaws with similar jaws of different sizes, hence a single body portion and a plurality of interchangeable jaws constitute a complete set of wrenches.

As shown, the improved wrench consists of a substantially rectangular body 11 having a handle 12, preferably formed integral therewith, extending from one end, and sharp teeth 50 or serrations 13 formed on the other end. A

metal yoke 14 straddles the rectangular body 11, and is pivotally secured to said body by a pin 15, which extends through the body and the parallel side walls 16 of said yoke. The intermediate portion 17 of said yoke bridges 55 the edge 18 of the body 11 and is spaced a suitable distance therefrom, as shown.

The shank 19 of a detachable gripping jaw 21 is adapted to be inserted between the intermediate portion 17 of the yoke 14 and the body-edge 18. The head 22 of said gripping jaw overlies the end 13 of body portion 11, said head having serrations or teeth 23 formed thereon to co-operate with those on the body to grip an object therebetween. The shank 19 of the gripping jaw 21 is provided on its outwardly disposed edge with a longitudinal groove 24 into which extends the free end of a leaf spring 25, secured on the under side of the intermediate portion 17 of the yoke 14, whereby said gripping jaw is held yielding 70 against the edge 18 of the body 11. The yoke 14 is removably held in place over the shank 18 by a suitable pin or screw 26, which extends through the side walls 16 of said yoke 75 and an opening 27 provided therefor adjacent the forward end of the body 11.

A trigger member 28 is mounted within an irregular slotted opening 29 extending laterally through the body portion 11. Upon reference to Fig. 1, it will be noted that the trigger member 28 preferably comprises a head 31 having large transverse serrations or teeth 32 on its outwardly directed face, and an intermediate portion 33 which extends longitudinally in the slotted opening 29 and is curved, at 34, substantially at right angles to said intermediate portion to provide a finger piece 35, which extends through an opening 36 in a suitable closure plate 37 mounted over said slotted opening. A pin 38 anchored in body 11 extends through an arcuate slot 39 in trigger member 28 to retain said member in place, and a suitable compression spring 41 normally retains said trigger in the position shown, with its head portion 31 projecting beyond the edge 18 of the body 11. The serrations or teeth 32 are adapted to co-operate with similar serrations or teeth 42, provided on one face of shank 19 to hold 100

securely the gripping jaw 21 in any adjusted position, relative to the body 11.

Adjustment of the gripping jaw is attained by engaging the operating finger 35 with one finger of the hand holding the wrench, and upon drawing said operating finger toward the handle, the head 31 of the trigger member is moved into the body 11, thus disengaging the teeth thereon from the shank. The thumb of the same hand is then placed upon the knurled portion 43 provided adjacent the free end of the shank, and the gripping jaw is moved longitudinally of the body 11 to increase or decrease the distance between the gripping faces 13 and 23. After adjusting the gripping jaw, the finger piece 35 is released and the teeth 32 again engage teeth 42 to hold the gripping jaw adjusted. It will be noted that the trigger pivots upon the curved portion 34 which seats in the similarly curved end of the slotted opening 29.

As shown in Fig. 4, the serrations 32 and 42 are angularly disposed transversely of their respective parts to insure proper gripping and relieve the strain imposed thereon while the wrench is in use.

It can readily be understood that a wrench constructed in the manner described in the foregoing may readily be adjusted with one hand, and by removing the screw 26 the yoke 14 may be swung about its pivot 15 substantially to the position shown in Fig. 2 to allow for the removal of the gripping jaw 19 and insertion, in its stead, of one of a different size. The entire device is of simple, strong construction having few working parts.

Although an exemplary form of the improved wrench has been shown in the accompanying drawing and described in detail in the foregoing specification, it is to be understood that certain modifications in detail structure may be embodied therein without departing from the spirit of the invention or the scope of the appended claims.

45 I claim:

1. A wrench comprising, in combination, a handle having a fixed jaw, a yoke pivotally secured to said handle adjacent said jaw, a movable jaw having a shank insertable through said yoke, teeth on said shank, said handle having a slot therein, a trigger in said slot, a head on said trigger, teeth on said head, a socket in one wall of said slot providing a bearing surface for said trigger, a finger piece on said trigger extending out of said slot through a cover plate thereover, a spring between said trigger, adjacent the head, and the cover plate, adapted to urge the teeth on said head into engagement with the teeth on said shank, and a pin in said handle passing through a slot in said trigger to guide said trigger in its movement.

2. A wrench comprising, in combination, a handle having a fixed jaw, a yoke pivotally secured to said handle adjacent said jaw, a

movable jaw having a shank insertable through said yoke, said shank extending longitudinally of said handle, angularly arranged teeth on said shank, a trigger mounted in said handle, a head on said trigger having teeth thereon adapted to co-operate with the teeth on said shank, a finger piece on said trigger extending outwardly of said handle on the side opposite to said shank, means to guide movement of said trigger including a fixed pin and a slot arrangement, and a spring operating to retain normally, the teeth on said head in engagement with the teeth on said shank to prevent displacement of said shank.

70 In testimony whereof I affix my signature.
